Application August 21, 1952, Serial No. 305,638

9 Claims. (Cl. 229—14)

This invention relates to new and useful improvements in containers and more particularly to a container made of cardboard, paper board or the like, for containing ice for cooling receptacles filled with beverages and similar articles stored in the carton.

Containers which may hold ice to cool articles, such as meat, food, medicine, beverages or other items which must be kept cool, are often needed for storing and cooling such items. Since such containers are often transported from place to place, as when used to carry beverages for consumption at picnic outings, shipping fish or fowl or transporting medicines, and the like, the containers should be light in weight so that they may be easily portable and adapted to air transport. Furthermore, since they may be subjected to rough handling they should be rugged in construction and capable of being locked closed. They should also lend themselves to stacking. Moreover, since the articles may be stored in the containers for prolonged periods of time before being used, the construction of the containers must be such that the passage of heat into the interior of the containers is at an exceedingly slow rate so that the rate of melting of the ice which cools the contents will be as slow as possible. Containers presently used for containing ice for cooling articles stored in the containers are made of metal and are, therefore, very heavy. In addition, their cost of manufacture is relatively high.

It is desirable, therefore, that a container be provided which is strong but relatively light in weight which will hold ice for prolonged periods of time, and which may be easily and economically manufactured, and such are objects of this invention.

It is also an object of this invention to provide a new and improved container made of paper board or the like for containing ice to cool articles stored in the container.

A further object of the invention is to provide a container of the character described which may be assembled from a plurality of easily assembled knocked down parts, so that the parts may be shipped in flat knocked down condition and may be erected and assembled at the point of use.

Another object of the invention is to provide a carton for containing ice made of corrugated paper board and having spaced air insulating chambers for preventing the passage of heat into the interior of the carton.

Still another object of the invention is to provide a new and improved paper board carton having spaced inner and outer walls providing insulating air chambers therebetween.

A particularly important object of the invention is to provide a new and improved carton in which a moisture impervious paper board or like tank is disposed in a cardboard container, the container and the tank having flaps which space the walls of the tank from the walls of the container to provide heat insulating air spaces or chambers therebetween.

Additional objects and advantages of the invention will be readily apparent from the reading of the following

2
description of a device constructed in accordance with the invention and reference to the accompanying drawings thereof, wherein:

5 Figure 1 is a perspective view of a container, constructed in accordance with the invention, for containing ice to cool articles stored in the container,

Figure 2 is a vertical sectional view of the container taken on the line 2—2 of Figure 1,

10 Figure 3 is a vertical sectional view of the container taken on the line 3—3 of Figure 2,

Figure 4 is a bottom plan view of the container,

15 Figure 5 is a perspective view of the container with the top removed and with portions of the container broken away to show the tank in position,

Figure 6 is a perspective view of the moisture impervious tank, and

Figure 7 is a plan view of a blank for forming the outer container.

20 In the drawings, the numeral 10 designates a container which is provided with a cover 11 and a moisture impervious tank 12. The container 10 is formed of a blank 13 cut from a sheet of material, preferably cardboard or the like, perforated and scored and ready for assembly. As clearly shown in Figure 7, the container blank is scored 25 to provide a back wall panel 14, an adjacent end wall panel 15, a front wall panel 16 substantially identical in size with the back side wall panel 14, a second end wall panel 17 adjacent the front wall panel, and a flap 18. The various wall panels are outlined by vertical imperforate scored lines 19 which provide for ready folding of the container blank into the rectangular form shown in Figures 1, 4 and 6, whereby the flap 18 may be secured by staples 20, or in any other suitable manner, to the inner surface of the back wall panel 14 to form the rectangular walls of the container 10.

25 Integral bottom closure portions 21 and 22 are formed integral with the back and front wall panels 14 and 16, respectively, and are defined by the imperforate scored fold lines 23 and 24, respectively. The upper bottom closure portion 21 overlies the lower bottom closure 22 (Figures 2 and 3). A pair of opposed bottom closure flaps 25 and 26 are formed integral with the end wall panels 15 and 17, respectively, and are defined by the transverse imperforate scored lines 27 and 28, respectively. The bottom closure flaps 25 and 26 are provided with reduced or narrowed end portions 29 and 30, respectively, which are adapted to pass through the perforation or slot 31 in the lower bottom closure portion 22. The reduced end portions 29 and 30 are each provided with a pair of imperforate scored fold lines 32 which enable the reduced end portions to be bent up and through the slot 31 and then down to lie between the upper and lower bottom closure portions 21 and 22, as clearly shown in Figure 2. It will be evident that when the upper bottom closure portion 21 is folded down to abut the reduced end portions, the end portions are held fast thereby, and the bottom structure is positively locked in erected position. It will also be evident that the reduced end portions space the upper and lower bottom closure portions from each other to form an air space or chamber 33 therebetween.

30 Upper rectangular flanges 34, 35, 36 and 37 are formed integral with the wall panels 14, 15, 16 and 17, respectively, and are defined by the transverse imperforate scored fold lines 38, 39, 40 and 41, respectively. The upper flanges 34, 35, 36 and 37 are provided with fold lines 42 which permit the horizontal portions 43, 44, 45 and 46, respectively, to overlie the upper edges of a rectangular liner having walls 47, 48, 49 and 50 disposed in the container 10 contiguous to the front, back and end wall panels of the container. The flanges are bent downwardly and inwardly to overlie the upper ends of the liner walls. The liner walls 47 to 50 may be integral

and cut from a sheet of material, preferably cardboard or the like, and scored to allow the walls 47 to 50 to be disposed into a roughly rectangular shape to form the liner.

It will be apparent now that the rectangular upper flanges will retain the liner walls in position and that the lower ends of the liner walls in turn will prevent the upper bottom closure portion 21 from being bent upwardly to free the reduced end portions 29 and 30 of the bottom closure flaps 25 and 26.

A pair of elongate tongue members 51 and 52 may be cut out or formed in the end wall panels 15 and 17, respectively, such tongue members extending to the fold lines 42 of the upper flanges 35 and 37. The tongue members are adapted to extend upwardly through slots 53 and 54 in the cover 11, then be bent downwardly around the outer end flanges 55 and 56 of the cover and then inwardly and upwardly inside the cover flanges so that the free end portions of the tongues may be disposed between the cover flanges and the end wall panels 15 and 17 to thus retain the cover in place. The cover 11 also has side flanges 57 and 58 which may extend over and abut the side wall panels 14 and 16.

The tank 12 is formed of a single substantially rectangular sheet of any suitable moisture impervious material, such as waxed paper board, and is folded in the manner shown in Figures 5 and 6 so that the tank will hold water without leaking. The tank includes a rectangular bottom 59, end walls 60 and 61, a front wall 62 and a back wall 63. The front wall 62 is connected to the side walls 61 and 62 by the folded triangular flap portions 64 and 65, and the back wall 63 is connected by similar flap portions 67 and 68 to such side walls. The front wall 62 is provided with a retaining flange 66 and the back wall with a flange 69 which fold outwardly and then downwardly over the upper portions of the triangular flap portions to retain them in their folded positions, the tank flange 66 being disposed adjacent and abutting the container flange 36 and the tank flange 69 adjacent and abutting the container flange 34 when the tank is inserted into the container.

It will be seen now that the container flanges 35 and 37 space the end walls 60 and 61 of the tank from the liner walls 48 and 50, respectively, so that heat insulating air spaces or chambers 70 and 71 are formed therebetween. Similarly, the tank flange 66 and the container flange 36 space the front wall 62 of the tank from the liner wall 49, and the tank flange 69 and the container flange 34 space the tank rear wall 63 from the liner wall 47 to form the heat insulating air spaces or chambers 72 and 73, respectively. The four sides and the bottom of the tank being surrounded by the air chambers 33, 70, 71, 72 and 73, in which the air is, of course, substantially at rest, the air chambers insulate the tank and reduce flow of heat into the tank to melt the ice which may be contained in the tank.

A rectangular moisture impervious cover plate 74 rests upon the upper portions of the tank flanges 66 and 69 and upon the upper edges of the end walls 60 and 61 of the tank. The flanges 66 and 69, together with the triangular flap portions which they overlie, provide relatively broad, firm supporting surfaces for the cover plate running along the front and back walls of the tank and container. The cover 11, of course, overlies the cover plate 74 and holds it in place, the tank being of such height that the cover plate is disposed between the liner walls and between the cover and the flanges 66 and 69 and the upper edges of the end walls 60 and 61 of the tank.

If desired, a layer of foil metal, such as aluminum or tin foil, may be provided to cover the inner surfaces of the tank 12 to provide moisture imperviousness and increased insulating value to the tank.

The container may be easily assembled by bending the blank 13 along the vertical fold lines 19 to place

the wall panels 14, 15, 16 and 17 in rectangular form and then stapling the panel flap 18 to the rear wall panel 14. The upper bottom closure 21 is bent inwardly between the wall panels and then the lower bottom closure 22 is bent perpendicular to the wall panels. The bottom closure flaps 25 and 26 are then bent inwardly and their reduced end portions 29 and 30 are passed through the slot 31 and bent downwardly to lie over the lower bottom closure 22. The upper bottom closure 10 is then moved into parallel relationship with the lower bottom closure portion 22 and over the reduced end portions of the closure flaps. The liner with its walls 47, 48, 49 and 50 is then inserted into the container and the flanges 34, 35, 36 and 37 are bent over and down over the upper portions of the liner walls. The tank 12 is then placed in the container, ice and the articles to be cooled are placed in the tank, the moisture-proofed cover 74 is placed over the tank, and finally the cover 11 is placed in position on the container, the tongue members 51 and 52 being folded around the cover flanges to hold the cover 11 on the container.

It will thus be seen that a container for holding ice and articles to be cooled has been provided which is made of cardboard or the like, and is easily assembled from 25 a plurality of scored blanks which form a container 10, liner walls, and a moisture-proof tank 12. It will also be seen that the container is light in weight but of strong, rugged construction, the liner walls reinforcing the container, and that the contents of the tank are well insulated 30 by means of the air chambers beneath and on the sides of the tank which minimize the passage of heat from without the container into the tank.

The foregoing description of the invention is explanatory only, and changes in the details of the construction 35 illustrated may be made by those skilled in the art, within the scope of the appended claims, without departing from the spirit of the invention.

What we claim and desire to secure by Letters Patent is:

40. A container having a pair of side walls and a pair of end walls integral with said side walls, said walls being disposed in vertical rectangular form, a pair of bottom closure portions, each of said bottom closure portions being integral with one wall of one pair of walls, said bottom closure portions being disposed in horizontal planes, one of said bottom closure portions being superposed above the other, a pair of flaps, each of said flaps being integral with one wall of the other pair of said walls, the lowermost of said bottom closure portions having an aperture therethrough, said flaps extending below and abutting the lowermost of said bottom closure portions, said flaps having end portions extending vertically upwardly and inwardly of the container through said aperture and horizontally in opposite directions between 45 said bottom closure portions, said end portions of said flaps spacing the uppermost bottom closure portion from the lowermost bottom closure portion to form an air space therebetween, and an inner container fitting closely in said container and having a closed bottom resting upon 50 and holding the uppermost bottom closure portion of the container in engagement with and holding the end portion of the flaps confined between said uppermost bottom closure portion and lowermost bottom closure portions.

55. In a device for cooling and storing articles: a container having a pair of side walls and a pair of end walls integral with said side walls, said walls being disposed in vertical rectangular form, a pair of bottom closure portions, each of said bottom closure portions being integral with one wall of one pair of walls, said bottom closure portions being disposed in horizontal planes, one of said bottom closure portions being superposed above the other, a pair of flaps, each of said flaps being integral with one wall of the other pair of said walls, the lowermost of said bottom closure portions having an aperture therethrough, said flaps extending below and abutting

the lowermost of said bottom closure portions, said flaps having end portions extending vertically through said aperture and horizontally in opposite directions between said bottom closure portions, said end portions of said flaps spacing the uppermost bottom closure portion from the lowermost bottom closure portion to form an air space therebetween, vertical liner walls in said container having lower edges resting on said uppermost bottom closure portion to hold said uppermost bottom closure portion in engagement with the end portions of the flaps whereby the flaps are locked in place, each of said liner walls being disposed parallel to and abutting a wall of said container, each of said container walls having an integral flange extending horizontally over the upper edge of its abutting liner wall, each of said flanges having an end portion extending downwardly and abutting the liner wall adjacent its container wall, each liner wall disposed between a container wall and the end portion of the container wall flange, and a substantially rectangular tank of water impervious material disposed in said container and having a bottom resting on said uppermost bottom closure portion of the container and four substantially vertical walls, the end portions of the container wall flanges extending downwardly between adjacent walls of the container and of the tank whereby air chambers are formed between said adjacent walls.

3. The device of claim 2 characterized in that the uppermost edges of the tank walls are disposed in a horizontal plane lower than the uppermost horizontal surfaces of said container wall flanges, and a moisture impervious rectangular cover plate resting on said uppermost edges of the tank walls and disposed between said end portions of said container wall flanges.

4. The device of claim 2 characterized in that the uppermost edges of the tank walls are disposed in a horizontal plane lower than the uppermost horizontal surfaces of said container wall flanges, a moisture impervious rectangular cover plate resting on said uppermost edges of the tank walls and disposed between said end portions of said container wall flanges, the flanges of one pair of container walls each having a tongue member, and a cover having a top and flanges depending therefrom and abutting adjacent container walls, said cover having a pair of apertures, each of said tongue members being adapted to extend upwardly through one of said apertures downwardly abutting the outer surface of an adjacent cover flange inwardly beneath the lower edge of the adjacent cover flange and upwardly between the adjacent cover flange and the adjacent container wall.

5. In a device for cooling and storing articles: a container having a pair of side walls and a pair of end walls integral with said side walls, said walls being disposed in vertical rectangular form, a pair of bottom closure portions, each of said bottom closure portions being integral with one wall of one pair of walls, said bottom closure portions being disposed in horizontal planes, one of said bottom closure portions being superposed above the other, a pair of flaps, each of said flaps being integral with one wall of the other pair of said walls, the lowermost of said bottom closure portions having an aperture therethrough, said flaps extending below and abutting the lowermost of said bottom closure portions, said flaps having end portions extending vertically through said aperture and horizontally in opposite directions between said bottom closure portions, said end portions of said flaps spacing the uppermost bottom closure portion from the lowermost bottom closure portion to form an air space therebetween, a substantially rectangular tank of water impervious material disposed in said container and having a bottom resting on the uppermost bottom closure portion and four substantially vertical walls, said tank bottom holding said uppermost bottom closure portion in engagement with the end portions of said flaps whereby said flaps are locked in place, said walls of said container having integral flanges extending downwardly between said walls of said container and said walls of said tank

whereby vertical air chambers are formed between adjacent walls of said tank and said container, the flanges of one pair of container walls each having a tongue member, and a cover having top and flanges depending therefrom and abutting adjacent container walls, said cover having a pair of apertures, each of said tongue members being adapted to extend upwardly through one of said apertures downwardly abutting the outer surface of an adjacent cover flange inwardly beneath the lower edge of the adjacent cover flange and upwardly between the adjacent cover flange and the adjacent container wall.

6. In a device for cooling and storing articles: a container having a pair of side walls and a pair of end walls integral with said side walls, said walls being disposed in vertical rectangular form, a pair of bottom closure portions, each of said bottom closure portions being integral with one wall of one pair of walls, said bottom closure portions being disposed in horizontal planes, one of said bottom closure portions being superposed above the other, a pair of flaps, each of said flaps being integral with one wall of the other pair of said walls, the lowermost of said bottom closure portions having an aperture therethrough, said flaps extending below and abutting the lowermost of said bottom closure portions, said flaps having end portions extending vertically through said aperture and horizontally in opposite directions between said bottom closure portions, said end portions of said flaps spacing the uppermost bottom closure portion from the lowermost bottom closure portion to form an air space therebetween, vertical liner walls in said container having lower edges resting on said uppermost bottom closure portion, each of said liner walls being disposed parallel to and abutting a wall of said container, each of said container walls having an integral flange extending horizontally over the upper edge of its abutting liner wall, each of said flanges having an end portion extending downwardly and abutting the liner wall adjacent its container wall, each liner wall disposed between a container wall and the end portion of the container wall flange, the flanges of one pair of container walls each having a tongue member, and a cover having top and flanges depending therefrom and abutting adjacent container walls, said cover having a pair of apertures, each of said tongue members being adapted to extend upwardly through one of said apertures downwardly abutting the outer surface of an adjacent cover flange inwardly beneath the lower edge of the adjacent cover flange and upwardly between the adjacent cover flange and the adjacent container wall.

7. In a device for cooling and storing articles: a container having a pair of side walls and a pair of end walls integral with said side walls, said walls being disposed in vertical rectangular form, a pair of bottom closure portions, each of said bottom closure portions being integral with one wall of one pair of walls, said bottom closure portions being disposed in horizontal planes, one of said bottom closure portions being superposed above the other, a pair of flaps, each of said flaps being integral with one wall of the other pair of said walls, the lowermost of said bottom closure portions having an aperture therethrough, said flaps extending below and abutting the lowermost of said bottom closure portions, said flaps having end portions extending vertically through said aperture and horizontally in opposite directions between said bottom closure portions, said end portions of said flaps spacing the uppermost bottom closure portion from the lowermost bottom closure portion to form an air space therebetween, vertical liner walls in said container having lower edges resting on said uppermost bottom closure portion, each of said liner walls being disposed parallel to and abutting a wall of said container, each of said container walls having an integral flange extending horizontally over the upper edge of its abutting liner wall, each of said flanges having an end portion extending downwardly and abutting the liner wall adjacent its container wall, each liner wall disposed between a container

wall and the end portion of the container wall flange, a substantially rectangular tank of water impervious material disposed in said container and having a bottom resting on said uppermost bottom closure portion of the container and four substantially vertical walls, the end portions of the container wall flanges between adjacent walls of the container and of the tank whereby air chambers are formed between said adjacent walls, the flanges of one pair of container walls each having a tongue member, and a cover having top and flanges depending therefrom and abutting adjacent container walls, said cover having a pair of apertures, each of said tongue members being adapted to extend upwardly through one of said apertures downwardly abutting the outer surface of an adjacent cover flange inwardly beneath the lower edge of the adjacent cover flange and upwardly between the adjacent cover flange and the adjacent container wall.

8. In a device for cooling and storing articles: a container having a pair of side walls and a pair of end walls integral with said side walls, said walls being disposed in vertical rectangular form, a pair of bottom closure portions, each of said bottom closure portions being integral with one wall of one pair of walls, said bottom closure portions being disposed in horizontal planes, one of said bottom closure portions being superposed above the other, a pair of flaps, each of said flaps being integral with one wall of the other pair of said walls, the lowermost of said bottom closure portions having an aperture therethrough, said flaps extending below and abutting the lowermost of said bottom closure portions, said flaps having end portions extending vertically through said aperture and horizontally in opposite directions between said bottom closure portions, said end portions of said flaps spacing the uppermost bottom closure portion from the lowermost bottom closure portion to form an air space therebetween, vertical liner walls in said container having lower edges resting on said uppermost bottom closure portion, each of said liner walls being disposed parallel to and abutting a wall of said container, each of said container walls having an integral flange extending horizontally over the upper edge of its abutting liner wall, each of said flanges having an end portion extending downwardly and abutting the liner wall adjacent its container wall, each liner wall being disposed between a container wall and the end portion of the container wall flange, and a single piece substantially rectangular tank formed of water impervious material disposed in said container and having a bottom resting on said uppermost bottom closure portion and four substantially vertical walls, adjacent vertical side edges of the walls being connected by triangular flap portions, two of said triangular flap portions being disposed parallel to one tank wall and the other two of said triangular flap portions being disposed parallel to the tank wall opposite said one tank wall, said one tank wall and said other tank wall having integral flanges extending outwardly over their adjacent pairs of triangular flap portions and then downwardly, each pair of triangular flap portions having their upper portions disposed between the adjacent tank wall and the associated flap portion, end portions of two oppo-

5 sitely disposed container wall flanges abutting said tank wall flanges to space said one and said another of said tank walls from their adjacent container walls, end portions of the other two oppositely disposed container wall flanges abutting the other two tank walls from their adjacent container walls.

9. A container having a pair of side walls and a pair of end walls integral with said side walls, said walls being disposed in vertical rectangular form, a pair of bottom closure portions, each of said bottom closure portions being integral with one wall of one pair of walls, said bottom closure portions being disposed in horizontal planes, one of said bottom closure portions being superposed above the other, a pair of flaps, each of said flaps being integral with one wall of the other pair of said walls, the lowermost of said bottom closure portions having an aperture therethrough, said flaps extending below and abutting the lowermost of said bottom closure portions, said flaps having end portions extending vertically through said aperture and horizontally in opposite directions between said bottom closure portions, said end portions of said flaps spacing the uppermost bottom closure portion from the lowermost bottom closure portion to form an air space therebetween, vertical liner walls in said container having lower edges resting on said uppermost bottom closure portion in engagement with the end portions of the flaps whereby said flap end portions are confined between said bottom closure portions to lock the flaps in position closing the bottom of the container, each of said liner walls being disposed parallel to and abutting a wall of said container, each of said container walls having an integral flange extending horizontally over the upper edge of its abutting liner wall, each of said wall flanges having an end portion extending downwardly and abutting the liner wall adjacent its container wall, each liner wall being disposed between a container wall and the end portion of the container wall flange, the flanges of one pair of container walls each having a tongue member, and a cover having a top and side flanges depending therefrom and abutting adjacent container walls, said cover having a pair of apertures, each of said tongue members being adapted to extend upwardly through one of said apertures downwardly abutting the outer surface of an adjacent cover flange inwardly beneath the lower edge of the cover flange and then upwardly between the cover flange and the adjacent container wall.
